GOLF COURSE

John E. Reilly, Levittown, N.Y.
(204 William Road, North Massapequa, N.Y.)
Filed July 5, 1960, Ser. No. 40,688
5 Claims. (Cl. 273—176)

This invention relates to golf courses and, more particularly, to a golf course arrangement for minimizing the time required for play and for minimizing the amount of walking required therefor.

Ordinarily, the number of players which a conventional golf course will accommodate is extremely limited due to the fact that each succeeding group of players must wait until the field ahead is clear before teeing off or approaching the green. This not only extends the amount of time required to play the round of golf, but also requires a larger expanse of land, and requires the players to walk a distance of three and one-half to four miles for each round of play. It is, therefore, an object of the present invention to provide a special purpose golf course having conventional tees, fairways, greens, and the like, which are arranged in a special manner which will allow for more rapid play, with minimum walking, and which may be laid out upon a relatively small parcel of land.

Still a further object of the present invention is to provide a commercial type of golf course which can be operated on a twenty-hour a day basis, will accommodate a relatively large number of players, and which can be substantially automatically controlled by the allotment of balls allowed for each hole.

An additional object of the present invention is to provide a special purpose golf course of the type described, in which the players never enter upon the fairways, thus minimizing the amount of walking required, and avoiding lapses of time between each group of players moving around the course.

A further object of the present invention is to provide a golf course which is extremely safe for use by beginner and advanced players, and which will require a minimum amount of upkeep and maintenance while handling a capacity number of players.

A more specific object of the present invention is to provide a special purpose golf course of the type described, in which putting areas identical to the putting areas of the main fairway are disposed adjacent to the tee area of each fairway, so that upon teeing off, each group of players may then move to the putting area thus freeing the fairway area for the next group of players.

Another specific object of the present invention is to provide a golf course of the aforementioned type, in which the fairways for each hole are disposed in substantially parallel side by side relationship with the tee area at one common end and the target green area for each wood shot at the opposite common end of the fairways, and including further a putting green area spaced apart from each fairway accessible to the tee area of each fairway, whereby the players may move directly to such putting green area for final approach and putting shots immediately following the tee and second shots from the fairway, in which each putting green area is an identical reproduction of the main green area of each fairway so that such final approach and putting shots may be taken from substantially identical positions as the lie of the ball in the fairway or main green area, without requiring the players to enter upon the fairways.

All of the foregoing and still further objects and advantages of this invention will become apparent from a study of the following specification, taken in connection with the accompanying drawing, wherein:

FIG. 1 is a perspective view of the layout of an 18-hole

2

golf course, made in accordance with one form of the present invention.

FIG. 2 is an enlarged fragmentary plan view of certain parts of the arrangement shown in FIG. 1.

5 FIG. 3 is a fragmentary plan view of a modified arrangement of a golf course made in accordance with the present invention.

Referring now to the drawing, and more particularly to FIGS. 1 and 2 thereof, a layout 10 for a golf course 10 made in accordance with one form of the present invention is shown to include a single group of fairways F1, F2 . . . F18, arranged in side-by-side parallel relationship.

Each fairway has a tee area T1, T2 . . . T18, at one 15 end and a target green area G1M, G2M . . . G18M, for wood shots, at the opposite end. Each fairway is further provided with main hazards H1M, H2M . . . H18M, adjacent to each respective target green area. In addition, some of the fairways, such as the three and four par holes, 20 are provided with individual fairway greens G1F, G2F . . . etc., and associated fairway hazards H1F, H2F . . . etc., that are shaped and arranged substantially identically to the corresponding target green and main hazard areas of each respective fairway. These fairway 25 greens and hazard areas are disposed intermediate each respective tee and target green area for purposes herein-after more fully described.

A putting green area G1P, G2P . . . G18P and accompanying hazards H1P, H2P . . . H18P, are spaced 30 apart from the tee area T1, T2 . . . T18, of each fairway. Each of these putting green and hazard areas is identical to the target green and hazard area of each respective fairway, and identical to each fairway green and hazard area of those fairways having such fairway green 35 and hazard areas, in the direction of approach from each respective tee area.

Each fairway is further provided with a fairway or second shot area S1, S2, S3 . . . S18, immediately adjacent to the respective tee area T1, T2 . . . T18 of each fairway, which fairway shot area is to be used in a manner hereinafter more fully described.

Additional hazards, such as water hazards 20, and rough 45 areas may be provided wherever desired on each of the fairways of the golf course. In addition, the centrally located club house 30 may be provided with sufficient parking space 32 for a large number of vehicles, and may include practice putting greens 34 for use by the players. A circuitous path 36 leads from the club house 30 toward the first fairway F1, where another practice green 38 is disposed and which may be used by players waiting 50 their turn at the first tee T1. A number of cross paths 40 extending between opposite sides of the circuitous path 36 are provided for the convenience of the players desiring to return to the club house in the middle of a round 55 of play.

Each tee area T1, T2, etc., is provided with a facility 42, which may be used as a shelter, and for dispensing balls to each of the players approaching the next tee during the round of play. Such facility may include an attendant or an automatic dispensing device which will dispense a predetermined number of golf balls to each player entering upon the tee area of each fairway, for purposes hereinafter more fully described.

65 One, two, three, or four players may participate as a party for each round of play. Starting at the first tee, an attendant or other dispensing device will supply each player with a specific number of golf balls to play the first hole which, for a par four hole includes five golf 70 balls apiece. Each player will take the first shot from the tee T1 and the distance thereof noted, such as by reference to indicating markers along the length of the fairway,

shrubs, or other similar markers. The markers are preferably coated with an iridescent paint which will be clearly visible during daylight playing and also during night time play under restricted lighting conditions. After driving the first shot from the tee T1 toward the target green area G1M, each player then has a choice of playing a second shot from the tee area T1 to a fairway marker corresponding in distance to the distance between the lie of his drive shot and the target green G1M; or the player may, instead, move to the fairway shot area S1 and play directly to the closer fairway target green G1F, with the object of making up only the yardage which would be required to place his first tee shot from its present lie onto the target green G1M.

After taking the second shot, the players of the party move to the putting green area G1P and place their balls in approximately the same position as the lie of their second shots relative to the target green area G1M or fairway green area G1F. Since the arrangement of the greens and hazards of each of the main, fairway, and putting green areas are identical in the direction of approach, the placement of the ball for the third stroke is substantially identical as would be the case if the players had entered upon the fairway F1 to take this third shot. In taking the third shot, each player will thus be required to chip or otherwise approach the putting green G1P, and following which the players will putt out in a conventional manner. All of the players in that party then proceed to the next tee area T2, where each player is given three golf balls for that hole. The reason that each player is provided with only three additional balls is that each player has at least one golf ball remaining from the last hole which was used for chipping and putting. This extra ball will be used on the second hole if needed. When moving to a par three hole, however, each player receives two balls, giving him a total of three balls. If a ball is hit out of bounds or into water, the player is allowed a second tee shot. He now lies two and moves to any one of the corresponding areas at the rear of the tee such as the approaching area, chipping area, traps, or putting green to finish out the hole.

It will now be recognized that play on this course is continuous, with no time wasted for players to clear the fairway or putting green ahead, whereupon each succeeding party may tee off immediately following the tee and second shots of each preceding group of players. As a result, each party may take all of the shots required for a full hole of play in a matter of a few minutes, with a minimum amount of walking, and with a minimum amount of delay searching or looking for lost balls. The circuitous path 36 provides a convenient directional control for the players and enables the players to return to the club house when ever desired. Each of the fairways is preferably approximately 300 yards long and 45 yards wide, thus providing the spaciousness and layout of full scale golf courses. The various tee areas, green areas, and fairways may also be contoured in any desired manner to add to the authenticity and reality of the golf source. Since the players do not move over the actual fairways and target green areas, such require a minimum amount of upkeep and maintenance even though the golf course is capable of handling capacity numbers of players.

Reference is now made to FIG. 3 of the drawing, which illustrates an 18-hole golf course 59 of as lightly modified form of an arrangement in which two nine hole groups of fairways 52 and 54 are arranged in back to back relationship with the tee areas thereof lying toward the center of the arrangement. Thus, the putting and chipping area 60 of one group of fairways 52 lies immediately adjacent to the chipping and putting areas 62 of the second group of fairways 54, which chipping and putting areas 60, 62, may be separated by a row of shrubs or trees 56. A circuitous path 58 extends around the en-

tire 18 holes of the arrangement between the respective tee area and putting area of each fairway. In this arrangement, the club house 64 is preferably located at the end of the golf course so as to be conveniently accessible to the first and 18th holes of play. This arrangement does not require a relatively long and narrow type of land arrangement required in the embodiment shown in FIGS. 1 and 2, but requires a parcel of land more square in outline.

10 It will also be recognized that in dispensing the correct number of balls to each player, the playing time of a complete round of golf can be carefully controlled since each player will be limited in the number of strokes that he can take during each hole. Also, by avoiding the necessity for any of the players to enter upon the fairways, the hazard of playing is minimized at the same time that the speed of play is increased.

15 While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

20 25 1. A golf course having adjacent parallel fairways, said fairways comprising holes of varied pars with corresponding varied distances, each hole having a tee area with the fairway associated therewith extending forwardly, laterally and rearwardly thereof, a distant target green situated at the far end of the fairway opposite said tee, and a putting or playing green situated to the rear of said tee, said putting green being of identical size, shape and contour as its associated target green and further including an approach area between the tee 30 and the putting green.

35 2. A golf course in accordance with claim 1, further comprising distance markers located along the edge of the fairway for each hole.

40 3. A golf course in accordance with claim 2, further comprising means to make said markers distinguishable under natural and artificial light.

45 4. A golf course comprising multiple fairways each having a maximum of two target greens and having adjacent to and to the rear of each fairway and extending oppositely from said target greens, a playing green, a putting green for each fairway, said putting green and target greens being identical in size, shape and contour, markers distinguishable in natural and artificial light, running parallel to the side of both the fairway and the 50 playing green.

55 5. A golf course having adjacent parallel fairways, said fairways comprising holes of varied pars with corresponding varied distances, each hole having a tee with the fairway associated therewith extending forwardly, laterally and rearwardly thereof, a distant target green at the far end of the fairway opposite said tee, a second target green located laterally of the drive line between said tee and said distant target green, said second target green being closer than said distant target green, a putting or playing green to the rear of said tee and having an approach area between the putting green and said tee, said second target green and said putting green being identical in size, shape and contour to said distant target green, distance markers located along the edge of the 60 65 fairway for each hole.
